PROCESS FOR THE PRODUCTION OF LACTAMS

Wallace F. Runge, Terre Haute, Ind., assignor to Commercial Solvents Corporation, New York, N.Y., a corporation of Maryland

No Drawing. Filed May 13, 1959, Ser. No. 812,786

5 Claims. (Cl. 260—239.3)

My invention relates to the production of lactams, and more particularly, to a process for the production of lactams by the Beckmann rearrangement of cyclic ketoximes using fuming sulfuric acid.

The conversion of oximes of acyclic or cyclic ketones by treatment with sulfuric acid into cyclic lactams is well known, this reaction being generally known as the Beckmann transformation, or rearrangement. Many modifications of this reaction have been tried, but most of them have been found to be impractical or uneconomical from a commercial point of view for various reasons. Practical application of this reaction requires that the operation be carried out economically; that is, with high conversions and yields and with the production of the cyclic lactams in a form easily recoverable in a relatively high state of purity. This is particularly the case in the production of caprolactam from cyclohexanone oxime, probably the most important application of this reaction from a commercial point of view.

The use of dilute sulfuric acid has been found generally unsuitable because of the undesirable effects from the presence of the water in the dilute sulfuric acid. Numerous attempts have been made to use concentrated and even fuming sulfuric acid. Because, however, of the large amounts of heat generated in the reaction when sulfuric acid of such concentration is employed, it has been found exceedingly difficult to prevent superheating with resultant decomposition. In an attempt to avoid the latter, it has been suggested that the Beckmann rearrangement be carried out in the presence of various organic compounds inert to sulfuric acid. This process also has been found to be disadvantageous because of the difficulty in selecting suitable compounds which are not affected by the sulfuric acid under the conditions of the rearrangement as well as the difficulty of separating the last traces of these compounds from the cyclic lactam.

My new and improved process for effecting the Beckmann rearrangement of cyclic ketoximes into cyclic lactams overcomes the various operating difficulties experienced in previous processes and at the same time gives high yields of the desired cyclic lactams in a form readily recoverable in the degree of purity required for products such as caprolactam to be used in the production of synthetic fibers.

My process is applicable generally to the Beckmann rearrangement of oximes of acyclic or cyclic ketones. Among the ketoximes which can be satisfactorily treated according to my improved process may be mentioned the following, but it is understood of course that the process is not limited specifically to these particular compounds: methyl-cyclopropanone oxime, methyl-cyclobutanone oxime, cyclopentanone oxime, 1-methyl-cyclopentanone oxime, 1-ethyl-cyclopentanone oxime, 1,1-dimethyl-cyclopentanone oxime, 1-methyl-2-ethyl-cyclopentanone oxime, 1,1,2 - trimethyl - cyclopentanone oxime, 1,1,3 - trimethyl-cyclopentanone oxime, cyclohexanone oxime, 1-methyl-cyclohexanone oxime, 1,1-dimethyl-cyclohexanone oxime, 1,3-dimethyl-cyclohexanone oxime, 1,4-dimethyl-cyclohex-

anone oxime, ethyl-cyclohexanone oxime, 1,1,3-dimethyl-cyclohexanone oxime, 1,1,4-trimethyl-cyclohexanone oxime, 1,2,4-trimethyl-cyclohexanone oxime, and heptanone oxime.

5 To effect the Beckmann rearrangement of the above ketoximes into the corresponding cyclic lactams, by my improved process, it is necessary to use sulfuric acid in concentration of not less than 99% sulfuric acid. I find it preferable to use 100% concentration sulfuric acid and

10 fuming sulfuric acid containing SO_3 in concentrations ranging from 1 to 10%. I have found that the use of fuming sulfuric acid of substantially higher concentrations lead to generally unsatisfactory results. While, therefore, I can add to my reaction mixture fuming sulfuric acid containing SO_3 of concentrations higher than 10%, it is important for most desirable results that the final concentration of the sulfuric acid used in my process to effect the Beckmann rearrangement of the cyclic ketoximes be not substantially greater than fuming sulfuric acid containing 10% SO_3 and preferably about 2-4% SO_3 .

The particular concentration of sulfuric acid used in my process determines to a large extent the temperatures at which the rearrangement can be effected, as well as the rate and method of mixing the ketoxime and sulfuric acid. For example, the use of 99% sulfuric acid requires substantially higher temperatures and longer periods of time in order to complete the Beckmann rearrangement than when higher concentration sulfuric acid, such as fuming sulfuric acid, are employed. Using 99% concentration acid, little or no reaction takes place at room temperature over fairly extended periods of time. When, however, the concentration is raised to 100% sulfuric acid, satisfactory yields are obtained at room temperature over a period of 8-10 hours.

35 When the concentration is raised to say fuming sulfuric acid containing 1 to 5% SO_3 the mixing of the ketoxime with the fuming sulfuric acid must be effected under carefully controlled conditions with sufficient cooling to maintain the mixture below approximately 50° C. until the reactants are completely 40 mixed, after which the mixture is raised to a temperature of not substantially in excess of 70° C., and preferably 40-60° C., and maintained at this temperature for periods of time ranging from 2 hours at 60° C. to 4 hours at 40° C.

45 As indicated above, I can carry out the Beckmann rearrangement reaction by my improved process at either relatively low or at elevated temperatures by changing the concentration of the acid. I can, for example, carry out my improved process by dissolving the ketoxime in sulfuric acid of 100% strength or higher at temperatures 50 below 50° C., and allowing the reaction to take place at temperatures ranging from 40-60° C. Using 100% acid, the reaction is quite slow (8 hours) and gives yields and product quality comparable to those obtained at elevated 55 temperatures. When fuming sulfuric acid (1%; 2%; 4.5% SO_3) is used, significantly higher yields are obtained with a slight improvement in product quality. The reaction time for acids of these concentrations varies from five to two and one-half hours, the time becoming progressively shorter as the acid strength increased.

60 The reaction can be effected much more quickly and with somewhat less satisfactory results by simultaneously adding the ketoxime, preferably in molten form, and the sulfuric acid of desired concentration in separate streams 65 into a reaction vessel at rates so as to give the desired ratio of ketoxime to sulfuric acid. By maintaining the temperature of the reaction mixture at 110-130° C. and continuously withdrawing reaction mixture from the vessel at a rate so as to maintain a residence time therein of 70 10-30 minutes, satisfactory results, both as to yield and quality are obtained.

A modification of the above two procedures consists of

first mixing the ketoxime and 99% sulfuric acid in the required proportions while maintaining the temperature of the mixture at not in excess of 50° C. The resulting mixture is then continuously introduced into a separate vessel simultaneously with an amount of fuming sulfuric acid sufficient to give in the reaction mixture a final concentration of sulfuric acid containing 1 to 10% SO₃ and, preferably, 2 to 4% SO₃. The temperature of this resulting mixture of ketoxime and fuming sulfuric acid is maintained at a temperature ranging from 40 to 70° C. and material is removed at a rate such that the total reaction mixture is maintained approximately constant and a residence time of 1 to 5 hours is obtained. At a temperature of 60° C., a residence time of approximately two hours gives satisfactory results.

Mole ratios ranging from 1 mole of ketoxime to 3.0 moles of sulfuric acid give good results in my process. I prefer to use mole-ratios within the range 1.0 to 1.5 H₂SO₄/1.0 oxime.

A better understanding of the nature of my invention can be had by reference to the following examples which illustrate my invention. I do not intend, however, to be limited to the particular ketoxime, procedures, amounts and conditions set forth therein, but I intend for the equivalents and variations obvious to those skilled in the art to be included within the scope of this specification and the attached claims.

Example I

To 719 g. (7.26 moles) 99% sulfuric acid was added 373 g. (3.3 moles) of powdered cyclohexanone oxime while holding the temperature of the resulting mixture below 30° C. with vigorous agitation and cooling, when necessary. The resulting mixture was then added at a rate of about 10 mls. per minute to a reactor consisting of a 500 ml. 4-necked round bottom flask with drain cock in the bottom and provision for heating and cooling, and fitted with a mechanical agitator, two dropping funnels and a thermometer and containing 145 g. of 34.2% caprolactam in 99% sulfuric acid heated to a temperature of 115° C. A total of 1073 g. of the reaction mixture was added to the reactor while withdrawing reaction mixture from the bottom thereof at a rate so as to keep a constant level of liquid in the reactor. During the reaction period of 75 minutes, the temperature range was maintained at 120-125° C. and reaction mixture was removed at the rate of approximately 9.5 ml. per minute, giving a residence time of approximately 10.5 minutes for the reaction mixture in the reactor. A total of 1216 g. of a very light colored crude reaction product was obtained. This crude reaction product was then slowly added to 1 to 4 volumes of saturated aqueous ammonium sulfate solution simultaneously with gaseous ammonia at a rate such that the pH was held between 7 and 8 and the temperature below 40° C. After neutralization, the precipitated ammonium sulfate was removed by centrifugation and the filtrate allowed to separate into layers. The aqueous layer was removed and used for subsequent neutralizations. Upon distillation under reduced pressure the upper oil layer gave 69% crude caprolactam, 29% water and 2% undistillable residue. This amounted to a 94% yield of crude caprolactam containing 0.14% oxime, 68 p.p.m. volatile base and having a permanganate requirement of 0.3% (i.e., the amount of potassium permanganate required in the treatment of crude caprolactam to enable it to pass permanganate time specification).

The crude product obtained as above described was next treated in the form of a 25% aqueous solution with the required amount of potassium permanganate, filtered, subjected to deionization, and the water then removed by distillation under reduced pressure followed by reflux at 165° C. and 30 mm. to remove volatile base. Distillation at reduced pressure then gave specification grade caprolac-

tam (caprolactam containing no more than 0.0025% oxime, and 25 p.p.m. volatile base).

Example II

To 484 g. (4.95 moles) fuming sulfuric acid containing 2.08% SO₃ was added 3.73 g. (3.3 moles) cyclohexanone oxime over a period of 100 minutes while maintaining the temperature of the resulting mixture at about 30° C. After the addition was complete, the mixture was maintained for an additional 30 minutes at a temperature of 35-40° C. in order to complete solution of the oxime. After complete solution, the reaction mixture was maintained at a temperature of 35-37° C. for an additional period of 3½ hours. The resulting reaction mixture was treated as described in Example I. A 95% yield of crude caprolactam having a permanganate requirement of 0.04%, containing no unconverted oxime and only 36 p.p.m. of volatile base was obtained.

Example III

To 350 g. 99% sulfuric acid was added 378 g. of powdered cyclohexanone oxime over a period of 40 minutes while holding the temperature at about 30° C. The resulting mixture was stirred for an additional two hours while maintaining the temperature at 30-35° C. in order to complete solution of the oxime. To the resulting solution was then added 134 g. fuming sulfuric acid containing 20% SO₃ dropwise over a period of 40 minutes while holding the temperature at about 20-25° C. during the first 30 minutes and then permitting the temperature to rise to 40° C. The resulting mixture was then allowed to stand at a temperature of 40° C. for a period of 3½ hours after which it was neutralized as described in Example I with ammonium sulfate solution to a final pH of 7.5. The resulting oil was isolated and distilled to yield a 93.6% crude caprolactam having a permanganate requirement of 0.03% and containing 0.001% oxime, and 34 p.p.m. volatile base.

Example IV

The reactor described in Example I was charged with 142 g. of 34.2% caprolactam in 99% sulfuric acid and the mixture heated to 115° C. To the heated mixture was then simultaneously added through separate dropping funnels 339 g. (3.0 moles) molten cyclohexanone oxime and 445 g. (4.5 moles) 99% sulfuric acid. The temperature of the reaction mixture was maintained at 115-125° C. during the period of the addition which lasted 80 minutes. The reaction product was removed from the bottom of the reaction vessel at the rate of approximately 7.5 ml. per minute, thus giving a residence time of approximately 13.4 minutes. A total reaction product of 924 g. was obtained, neutralized, and treated as described in Example I. A 91% yield of crude caprolactam having a permanganate requirement of 0.6% and containing 0.34% oxime and 91 p.p.m. volatile base was obtained.

Example V

To 350 g. (3.325 moles) 99% sulfuric acid was added 373 g. (3.3 moles) powdered cyclohexanone oxime over a period of approximately 90 minutes while maintaining the temperature at approximately 30° C. while stirring the mixture until solution was complete. The reactor described in Example I was charged with 268 g. of a 42% solution of caprolactam in fuming sulfuric acid containing 2.44% SO₃. This mixture was heated to 60° C. and the solution of cyclohexanone oxime in 99% sulfuric acid prepared as above described was added at a rate of about 1.4 ml. per minute to the heated solution in the reactor simultaneously with 165 g. fuming sulfuric acid containing 17% SO₃ at a rate of approximately 0.25 ml. per minute. A total of 10 ml. of feed mix was added before beginning removal of reaction mixture from the bottom of the reactor and this level

was maintained in the reactor throughout the run, which lasted for a period of six hours. The reaction temperature was maintained at 60-64° C. and the residence time was 117 minutes. The resulting reaction mixture was neutralized and recovered as described in Example I. A yield of 92.8% crude caprolactam was obtained having a permanganate requirement of 0.8%, an oxime content of 0.002%, and containing 40 p.p.m. volatile base.

The following table shows the results of additional runs made in accordance with the procedures illustrated above in Examples I-V inclusive under varying reaction temperature conditions.

Cone. of Acid	Mol Ratio, Acid to Oxime	Temp., ° C.	Time Req'd., hrs.	Yield, Percent	Perm. Req., Percent	Oxime, Percent	Volatile Base, p.p.m.
100%	1.5 to 1.0	40	8	91	0.05	0.005	53
1% SO ₃	1.5 to 1.0	40	5	97	0.05	0.001	32
4.5% SO ₃	1.5 to 1.0	40	2½	95.2	0.01	0.001	21
99%	1.1 to 1.0	115-125	1 16.0	89	4.8	1.94	168
99%	1.3 to 1.0	115-125	1 13.2	87.6	2.2	0.95	172
99%	1.65 to 1.0	115-125	1 14.0	91.5	2.0	0.86	168
99%	2.2 to 1.0	115-125	1 11.0	90.5	0.8	0.37	157

¹ Minutes.

Examination of the results reported above shows that my improved process gives high yields of caprolactam of degree of purity close to that required for use in the production of synthetic fibers. This markedly simplifies any final purification required to give a salable product. In fact, the "crude oil" obtained when my process is carried out at low temperatures is of such high quality the distillation of the crude oil to give crude caprolactam can usually be eliminated, thus saving operational time and cost and increasing the overall yield.

Now having described my invention, what I claim is:

1. In a process for the production of lactams from cyclic ketoximes selected from the group consisting of cyclo-aliphatic ketoximes and alkyl substituted cyclo-aliphatic ketoximes, the cyclo-aliphatic portion of the ketoxime containing from 3 to 7 carbon atoms inclusive, the steps which comprise dissolving the cyclic ketoxime in sulfuric acid having a concentration of from about 99 to about 105% sulfuric acid at a temperature ranging from about 40° to about 60° C. in a ratio of 1 mole of said cyclic ketoxime to 1 to 3.0 moles of said sulfuric acid and permitting said mixture to react at temperatures ranging from about 40° to about 70° C.

2. In a process for the production of lactams from cyclic ketoximes selected from the group consisting of cyclo-aliphatic ketoximes and alkyl substituted cyclo-aliphatic ketoximes the cyclo-aliphatic portion of the ketoxime containing from 3 to 7 carbon atoms inclusive, the steps which comprise dissolving the cyclic ketoxime in sulfuric acid having a concentration of from about 99 to about 104% sulfuric acid at a temperature from about 40° to about 60° C. in a ratio of 1 mole of said cyclic ketoxime to 1 to 3.0 moles of said sulfuric acid, adding to the resulting mixture sulfuric acid having a SO₃ concentration of from about 1 to about 10% in amounts such that the final concentration of sulfuric acid ranges from about 100 to about 105% sulfuric

acid and permitting the resulting mixture to react at temperatures ranging from about 40° to about 70° C.

3. In a process for the production of lactams from cyclic ketoximes selected from the group consisting of cyclo-aliphatic ketoximes and alkyl substituted cyclo-aliphatic ketoximes, the cyclo-aliphatic portion of the ketoxime containing from 3 to 7 carbon atoms inclusive, the steps which comprise continuously mixing the cyclic ketoxime in molten form with sulfuric acid having a concentration of from about 99 to about 105% sulfuric acid, said cyclic ketoxime and said sulfuric acid being mixed at a ratio of 1 mole of cyclic ketoxime to 1 to 3.0

moles of said sulfuric acid and at a temperature ranging from about 40° to about 60° C. and permitting said mixture to react at temperatures ranging from about 40° to about 70° C.

4. In a process for the production of lactams from cyclic ketoximes selected from the group consisting of cyclo-aliphatic ketoximes and alkyl substituted cyclo-aliphatic ketoximes, the cyclo-aliphatic portion of the ketoxime containing from 3 to 7 carbon atoms inclusive, the steps which comprise continuously mixing the said cyclic ketoxime in molten form with sulfuric acid having a concentration of from about 99 to about 104% sulfuric acid in a ratio of 1 mole of cyclic ketoxime to 1 to 3.0 moles of said sulfuric acid at a temperature ranging from about 40° to about 60° C. and adding the resulting solution to a separate vessel simultaneously and co-ordinated with the addition thereto of sulfuric acid having a SO₃ content ranging from about 1 to about 10%, the amounts of said sulfuric acid addition being regulated to give a final sulfuric acid concentration of from about 100 to about 105% sulfuric acid and a final quantity of sulfuric acid equal to 1 to 3.0 moles of sulfuric acid for each 50 mole of cyclic ketoxime and permitting the reaction mixture to react at temperatures ranging from about 40° to about 70° C.

5. The process of claim 4 wherein the reaction is conducted at a temperature ranging from about 40° to about 70° C. for a period of from about 1 to about 5 hours.
